CIGARETTE ASHTRAY AND HOLDER

Herbert Paul Ryan, Suffern, N. Y.

Application July 13, 1937, Serial No. 153,390

4 Claims. (Cl. 131—51)

The present invention pertains to holding devices and receivers adapted for embodiment in tobacco users' appliances and more particularly to such devices for holding cigarettes and the ashes from the same.

As is well known, the general design of cigarette ash trays provides for the support of the cigarette or cigar in extensions from the side of the tray and, often times, when the cigarette or cigar is placed in these supports, the burning cigarette or cigar continues to smoulder and eventually drops from its supporting means causing damage or fire.

The primary object of the present invention is, therefore, to provide an ash tray or receptacle having means thereon for holding the cigarette in the receiver.

A still further object of the invention is to provide a detachable guard whereby the cigarette is caused to be deposited into the ash receiving receptacle.

Other objects of the invention will more readily appear from an understanding of the following description and accompanying drawing illustrating an embodiment of the invention and the invention will be more specifically set forth in the accompanying claims.

Referring to the drawing:

Fig. 1 is a side elevation partly in section illustrating the invention in combination with an ash receiving receptacle;

Fig. 2 is a top plan view partly in section and taken substantially on line 2—2 of Fig. 1;

Fig. 3 is a perspective view of the detachable guard; and

Fig. 4 is a sectional view of the spring holding means and illustrating a cigarette supported therein.

Referring to the drawing for a more detailed description thereof, the numeral 1 represents an ash receiving receptacle, the upper edge 2 of which is rolled to form a beaded reinforcement around the periphery thereof. The bottom portion 3 of the receptacle is substantially flat to aid in maintaining the receptacle in an upright position. A recess 4 is provided in the bottom portion 3 for receiving a weighted member 5 which member is secured to the lower end of the shaft 6, said weight tending to return the receptacle to an upright position should the same become tilted. The receptacle 1 is secured to the lower end of shaft 6 by passing said shaft through an orifice 4' and clamping the same against the raised portion of the recess 4 by a nut or the like 7.

In the upper end of the shaft 6 there is a collar 8 supported on the shoulder 9 and having in spaced relation a plurality of openings 10. The resilient supporting means 12 for holding the cigarette 13 has one end 14 attached to the receptacle 1 within spaced openings 15, and the opposite end 11 supported within the openings 10 of the collar 8. As clearly illustrated in Fig. 2 of the drawing, a pair of resilient supporting means 12, consisting of closely wound, flexible springs, are secured to the collar 8 and receptacle 1 and suitably spaced for supporting a cigarette therebetween. It is, of course, to be understood that a plurality of pairs of resilient means may be attached in the manner above described. The pairs of resilient means 12 when properly spaced provide substantially wedged shaped openings 16 for gripping and holding a cigarette or the like 13.

For presenting a finished appearance to the upper end of the shaft 6, a guard plate 17 suitably shaped is positioned on the upper end of said shaft above the collar 10 and is held in place thereon by means of the knurled nut 18, it being understood that the upper end of the shaft 20 is suitably threaded for receiving said nut. A conical shaped shield 19 is also positioned over the lower end of the shaft 6 which shield serves to form an enclosure means for the lower end of said shaft, nut 7, and recessed portion 4.

Positioned between each pair of the resilient supporting means 12 is a detachable guard 20 illustrated in perspective in Fig. 3 of the drawing, and it will be noted that said guard is secured on the beaded edge 2 of the receptacle by a pair of spring supported legs 21 and 22, which engage the inner portion of said receptacle, and an intermediate leg 23, which grips the outer portion of the receptacle. It is understood that, if desired, a guard 20 may be positioned between each pair of the resilient supporting means and secured to the receptacle in the manner above described. The portion 24 of the guard 20 is flared upwardly and outwardly from the edge 2 of the receptacle and is recessed as indicated at 25. When a cigarette or the like burns beyond its holding means, it will drop into the recessed portion of the guard as illustrated in dotted lines in Fig. 1, at which time the lighted end of the cigarette will remain within the wedge shaped opening 16 which will serve to extinguish the lighted end of the cigarette, thereby preventing fire or other damage.

From the above description it will be apparent that there is provided an attachment for

ash receiving receptacles which will effectively form a support and receiving means for a cigar, cigarette, or the like. The positioning of the cigarette between the resilient supporting means will assure the eventual deposit of the cigarette within the receptacle, thereby minimizing the liability for fire or other damage.

It is understood that this improvement is capable of extended application and is not confined to the exact showing of the drawing nor to the precise construction described and, therefore, such changes and modifications may be made therein as do not affect the spirit of the invention nor exceed the scope thereof as expressed in the appended claims.

What is claimed as new is:

1. A device of the character described, comprising, in combination, a substantially semi-spherical ash receiving receptacle having a beaded edge thereon, a shaft extending vertically from said receptacle, means for attaching one end of said shaft to said receptacle, a plurality of pairs of resilient members having one end attached to the beaded edge of said receptacle and the other end to a collar mounted in the upper end of said shaft, and guard member supported on said receptacle adjacent one of said resilient members.
2. A device of the character described, comprising, in combination, an ash receiving receptacle having a recess in the bottom portion thereof, a weighted member mounted within said recess, a shaft extending vertically from said receptacle and having one end attached thereto above the weighted member, a collar supported

on the opposite end of said shaft and having a plurality of perforations, a plurality of pairs of resilient members each having one end thereof attached to said collar and the other end thereof connected to said receptacle, and a guard member supported on said receptacle adjacent the place of connection of one of said resilient members.

3. A smoker's accessory comprising a cup-like receptacle, a substantially upright standard mounted within said receptacle and partially extending therefrom, a collar mounted on said standard near the free end thereof, a plurality of helically coiled essentially resilient members, each attached at one end thereof to said collar, radially extending toward and attached to peripheral parts of said receptacle, and at least one guard member on the periphery of said receptacle adjacent the place of attachment thereto of one of said resilient members.

4. A smoker's accessory comprising a cup-like receptacle, a substantially upright standard mounted within said receptacle and partially extending therefrom, a collar mounted on said standard near the free end thereof, a plurality of pairs of spaced helically coiled essentially resilient members, each attached at one end thereof to said collar, radially extending toward and attached to peripheral parts of said receptacle, and at least one guard member, engageable with and mounted on said peripheral parts of said receptacle near the place of attachment thereto of one of said resilient members.
